Primary Examiner — David G Muller(57) **CLAIM**

I claim the ornamental design for a wheel clamp, as shown and described.

DESCRIPTION

FIG. 1 is a front elevational view of a wheel clamp showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken line portions shown in FIGS. 2 and 5 form no part of the claimed design.
